UNITED STATES PATENT OFFICE.

WILLIAM F. SEIDEL, OF ELKHART, INDIANA.

AUXILIARY AIR AND MOISTURE VALVE FOR INTERNAL-COMBUSTION ENGINES.

1,245,988.

Specification of Letters Patent.

Patented Nov. 6, 1917.

Application filed October 30, 1916. Serial No. 128,515.

To all whom it may concern:

Be it known that I, WILLIAM F. SEIDEL, a citizen of the United States, residing at Elkhart, in the county of Elkhart and State 5 of Indiana, have invented certain new and useful Improvements in Auxiliary Air and Moisture Valves for Internal-Combustion Engines; and I do declare the following to be a full, clear, and exact description of the 10 invention, such as will enable others skilled in the art to which it appertains to make and use the same.

This invention relates generally to internal combustion engines, and more particularly to certain new and useful improvements in auxiliary air and gas valves used in connection with the same.

The primary object of the invention is to provide a valve of this character wherein 20 the use of springs and rubber or fiber packing washers are dispensed with.

Another object of the invention is to provide means whereby the water of condensation which may from time to time collect 25 within the valve, may automatically drain out of the same.

A further object of the invention is to provide a unique form of stop for limiting the movement of the movable valve member.

30 A still further object of the invention is to generally improve upon valves of this character by providing a device which will be of extremely simple, durable and inexpensive construction, one which is efficient 35 and reliable in operation, and well adapted to the purpose for which it is designed.

With these and numerous other objects in view, the invention resides in certain novel features of construction, and the combination and arrangement of parts as will 40 be hereinafter fully described and claimed.

In the accompanying drawings, forming a part of the application, and in which similar reference characters designate like parts 45 throughout the several views,

Figure 1 is a front elevation of a device constructed in accordance with this invention, showing the manner in which it is connected to the intake manifold of an internal combustion engine and to the air or steam space of the radiator of the engine;

Fig. 2 is an enlarged front elevation of the device;

Fig. 3 is a top plan view of the same; Fig. 4 is a vertical sectional view through 55 the device taken on the plane of the line 4-4 of Fig. 9, showing the valve in its opened position;

Fig. 5 is a similar view showing the valve in its closed position; 60

Fig. 6 is a vertical sectional view taken on the line 6-6 of Fig. 4.

Fig. 7 is a transverse sectional view taken on the line 7-7 of Fig. 9.

Fig. 8 is a similar view taken on the line 65 8-8 of Fig. 9;

Fig. 10 is a rear elevation of the device; and

Fig. 11 is a horizontal sectional view taken on the line 11-11 of Fig. 4. 70

Referring more particularly to the drawings, the numeral 1 represents a cylindrical valve chamber having a wall 2 at one end thereof provided with a centrally arranged circular opening 3 therein. The other end 75 of the chamber 1 is reduced and externally threaded as at 4 and provided with a notch 5, the purpose of which will be hereinafter described. Projecting from the diametrically opposite sides of the chamber 1 are 80 hollow stems 6 and 7, the stem 6 being externally threaded to adapt it for connection to the intake manifold A of an internal combustion engine, while the stem 7 is internally threaded to receive one end of a suitable 85 pipe-section 8 leading from the steam or air space of the radiator B of the engine. These hollow stems communicate with the interior of the chamber.

Arranged within the chamber 1 is a cylindrical valve 9 having an opening extending transversely therethrough and communicating with the inner open ends of the hollow stems 6 and 7. The inner end of the valve 9 is held in frictionally tight contact with 90 the interior side of the wall 2 of the chamber 1 by means of a disk 10, which is arranged within the chamber in a manner now to be described.

The opposite sides of the central portion 100 of the disk 10 are provided with outwardly extending central portions 11 and 12, the portion 11 bearing tightly against the valve 9, while the portion 12 is arranged in abutting relation to the inner side of a cap member 13 which is inserted upon the open end 105

of the chamber 1 and adjusted until the interior parts of the valve are in frictionally tight engagement. The valve 9 is thus held sufficiently tight against the wall 2 of the 5 chamber so as to prevent leakage through the opening 3 in said wall, and the valve 9 itself is sufficiently tight in the chamber to also prevent such leakage.

In order to drain the water or condensation which may from time to time collect in 10 the interior of the chamber from the same, the valve 9 is provided with a passage 14 which extends substantially longitudinally of the same with one of its ends in connection with the transverse passage in the valve, while the other end is disposed at the outer 15 end of the same. This passage 14 is disposed below the transverse passage in the valve and is given a slight downward inclination from its inner to its outer end so 20 that if any water or condensation collects within the valve itself it will be conveyed to the interior of the casing between the ends of the valve and the disk 10. This water 25 then passes through an aperture 15 arranged in the disk 10 into the space formed between the other side of said disk and the interior side of the cap 13, and from there it will slowly drain through the opening 16. 30 The inner side of the disk 10 is provided with an annular channel 17 which assists in conveying the water to the aperture 15.

Extending longitudinally and centrally from the inner end of the valve 9 is a shank 35 18, the inner end of which is provided with a plurality of circumferentially spaced transversely extending ribs or ridges 19, while the outer end of the shank 18 is reduced a small amount in diameter and externally threaded to receive a clamping nut 40 20, between the inner end of which and the exterior side of the wall 2 is disposed the hub portion 21 of an operating arm or lever 22. This hub portion 21 of the arm 22 is 45 provided with diametrically opposite pins or lugs 23 which are received in two of the longitudinal ridges 19 to prevent the arm from rotating with respect to the washer.

This construction of valves allows for 50 mounting the arm in any radially extending direction with respect to the shank. This will be found advantageous when the valve is being connected to the operating devices to be hereinafter described.

55 The arm 22 is provided with a series of apertures 24, one of which is to be connected in any convenient manner to one end of a link 25, the other end of the latter being connected in any convenient manner to the 60 throttle lever of the engine. Thus, whenever the throttle lever is actuated, the valve 9 is revolved a sufficient amount to either open or close the passage extending transversely therethrough into communication 65 with the inner open ends of the stems 6 and

7, depending upon which way said lever is operated.

Extending longitudinally from the outer end of the valve 9 at a point offset a short distance from the longitudinal axis of the 70 same is a pin 26 which is received in a notch 27 arranged at one edge of the disk 10 to limit the movement of said valve. Rotation of the disk 10 is prevented by the lug 28 which extends from one edge of the same 75 and is disposed in the notch 5 in the open end of the chamber 1, as hereinbefore referred to.

Air or steam conveyed from the radiator of the engine to the manifold thereof in this 80 manner and controlled automatically by the position of the throttle lever, will greatly add to the efficiency of the engine, as will be readily understood.

From the foregoing description, taken in 85 connection with the accompanying drawings, the construction and operation of the device will be readily understood without a more extended explanation. As numerous changes in form, proportion, and in the 90 minor details of construction may be resorted to without departing from the spirit of this invention, I do not wish to be limited to the construction herein shown and described other than as claimed. 95

I claim:—

A device of the class described comprising a cylindrical valve chamber having a wall at one end thereof provided with a centrally arranged opening, and its other end open and externally threaded, hollow stems 100 projecting from the diametrically opposite sides of said chamber, one of said stems being adapted to be attached to the intake manifold of an internal combustion engine, the other stem being adapted to be connected to the air space of the radiator, a rotary valve mounted within said chamber and having a passage extending transversely therethrough to communicate with the inner open 105 ends of said stems, a shank projecting longitudinally from the central portion of said valve and extending through said opening and provided with an arm adapted to be operatively connected with the throttle lever 110 of said engine, said valve being provided with a drain passage communicating with the lower side of the transverse passage therein for conveying the water of condensation from the same, a disk non-rotatably 115 mounted in said chamber and having centrally arranged outwardly projecting portions on its opposite sides, the projecting portion on its inner side being disposed in tight contact with the outer end of said valve, and a cap threaded upon the open end 120 of said chamber, the inner side of said cap bearing against the projecting portion on the outer side of said disk to hold the inner 125 end of the valve into frictionally tight en- 130

gagement with the interior side of the wall of said chamber, said disk and said cap being provided with apertures arranged substantially in communication with the lower 5 end of the drain passage in said valve to provide a means for draining off the water of condensation collected therein.

In testimony whereof I have hereunto set my hand in the presence of two subscribing witnesses.

WILLIAM F. SEIDEL.
